UNITED STATES PATENT OFFICE.

PATRICK H. CUSICK, OF OREGON, WISCONSIN.

RADIATOR.

1,328,789.

Specification of Letters Patent. Patented Jan. 20, 1920.

Application filed July 16, 1918. Serial No. 245,250.

To all whom it may concern:

Be it known that I, PATRICK H. CUSICK, a citizen of the United States, residing at Oregon, in the county of Dane, State of 5 Wisconsin, have invented certain new and useful Improvements in Radiators; and I do hereby declare the following to be a full, clear, and exact description of the invention, such as will enable others skilled in the art 10 to which it appertains to make and use the same.

This invention relates to radiators; and its main object, briefly stated, is the provision of a device of the character indicated, 15 embodying certain improved structural features whereby installation may be effected in a much smaller space than has heretofore been possible, and the number of parts around which cleaning must take place is 20 reduced.

According to the invention, the usual horizontal supply pipe for the steam or hot water, which ordinarily enters the section at the inlet end of the radiator at right 25 angles thereto, is replaced by a short vertical pipe section which enters the bottom of the said section and is connected to the main supply pipe, the latter being disposed beneath the floor of the room wherein the radiator is located. The passage of the heating medium through this pipe section is controlled by a valve in the usual way; but instead of arranging the valve to one side of, and in spaced relation to, the end section, as 30 is customary, it is incorporated in the said section itself. The usual feet of the end sections are omitted, and instead there is provided for each end section an enlarged, solid base or pedestal, which rests directly 35 on the floor, one base being formed with a passage wherein the end of the supply pipe is fitted, such passage opening into the interior of the radiator section and being controlled by the aforementioned valve. 40 Where a return pipe connection is provided, the other base is constructed with a similar passage in which the end of the vertical return pipe is received, so that not only is a saving of space obtained at both ends of 45 the radiator, but instead of having to clean around the feet of each end section and beneath the inlet and outlet pipes, it is merely necessary, with the present construction, to clean around the bases of the end sections, 50 which operation is much simpler and can be effected more rapidly and easily than is

the case with radiators of conventional type.

In the accompanying drawing:

Figure 1 is an end elevation, with parts 60 in vertical section, of a radiator constructed in accordance with the invention;

Fig. 2 is a front elevation thereof;

Fig. 3 is a view similar to Fig. 2, but showing the radiator equipped with a return pipe;

Fig. 4 is a front elevation of a further type of radiator to which the invention may be applied; and

Fig. 5 is a fragmental sectional view 70 showing a slightly different arrangement of the valve.

Referring more particularly to said drawing, 1 and 2 indicate the two end sections of the radiator, and 3 the intermediate sections, 75 all of which are, in the main, of conventional form, and are joined together by tie-rods 4 and 5, that are fastened at their terminals to upper and lower projecting webs 6 and 7 with which the said end sections are 80 provided. The bottom portion of each end section is enlarged to form a solid base or pedestal 8 or 9, which rests directly upon the floor of the room and which takes the place of the pairs of feet ordinarily provided. The base 8 of the inlet section 1 is formed with a vertical passage 10 having an angular extension or branch 11 leading from it, said extension opening, in turn, into an enlargement or chamber 12 provided 85 upon the lower front portion of the said section. The passage 10 is designed to receive the threaded end of a short inlet pipe section 13, which projects upward thereinto from the main supply pipe 14 for the heating medium, the latter being disposed beneath the floor, as shown in Fig. 1. The chamber 12 is substantially cylindrical in shape, and besides being open at its opposite ends, it is also open along its entire 90 inner side, so that it communicates directly with the interior of the section.

Under ordinary conditions, therefore, the heating medium would be free to flow through the pipes 14 and 13 and the main 105 and branch passages 10 and 11 into the chamber 12, and thence into the interior of the radiator section 1, through which it would circulate and from which it would pass by way of an opening 15 in the lower 110 portion of the section into the adjacent intermediate section 3. To control the flow, a

valve device is provided, which is disposed within the chamber 12 and preferably comprises a head or valve proper 16 mounted on the lower end of a rod 17 that projects 5 through the upper end of said chamber and is in threaded engagement with a bearing cap 18 fitted over said chamber end. It should be noted that the rod 17 extends diagonally upwardly and outwardly and is located in the plane of the radiator section proper, whereby a neat and inconspicuous mounting is had. The outer end of the valve rod is equipped with a handle 19, which, when turned, will cause the valve 16 10 to move alternatively toward or from its co-acting seat 20, the latter being located at the point where the branch passage 11 opens into the chamber 12.

The same, or substantially the same, arrangement is employed when the radiator is furnished with a return pipe connection, as represented in Figs. 3 and 4, in which case a short outlet pipe section 21 projects upwardly from the main return pipe (not shown) into a passage 22 formed in the base 9 of the section 2 at the outlet end of the radiator, the valve device being omitted and the upper end of the chamber 12 closed. The radiator illustrated in Fig. 4 is designed 25 for the circulation therein of hot water as the heating medium, and differs from the forms shown in Figs. 2 and 3 in which steam is to be used, only in that its several sections are in communication at both top and bottom instead of at bottom alone, so that separate description thereof is unnecessary.

Instead of forming the inlet section 1 with the cylindrical chamber 12 for the valve device, this chamber may be omitted, 40 and the valve device located in the base of said section below the circulation space, as represented in Fig. 5, with the result that the symmetrical appearance of the radiator is preserved. In such instance, both the

main and branch passages 10' and 11' are 45 vertical and overlap or extend past each other for a slight distance, at which point they are in communication. The branch passage 11' opens directly into the bottom of the circulation space within the radiator 50 section, and its front wall is provided with an opening to receive the bearing cap 18' wherein the valve rod 17' is mounted. This rod 17' is much shorter than the rod 17 in the first form, but is otherwise similar thereto, being equipped at its outer end with a handle 19' and at its inner end with a head or valve 16' for co-operation with the seat 20'. 55

I claim as my invention:

1. A radiator, comprising a plurality of 60 connected end and intermediate sections, each end section having an enlarged, solid pedestal integral therewith and adapted to rest directly upon the floor, tie rods holding said sections together the base of one end 65 section having extending through it a passage for the heating medium which opens at its lower end through the under face of said pedestal and communicates at its upper end with the circulation space within the 70 said section, the lower portion of said passage being designed to receive the projecting end of a transmission pipe for the heating medium.

2. A radiator section having an enlarged 75 solid pedestal integral therewith and adapted to rest directly on the floor, said pedestal being provided with a passage designed to register, at its lower end, with a heating medium supply pipe, a valve adapted to 80 close said passage, a valve rod attached to said valve and extending diagonally and upwardly in the plane of the radiator section and mounting means carried by the radiator, for mounting the valve rod. 85

In testimony whereof I affix my signature.

PATRICK H. CUSICK.
